UNITED STATES PATENT OFFICE.

WILLIAM S. TOWNSEND, OF ROCHESTER, PENNSYLVANIA, ASSIGNOR TO GUARANTEER
LIQUID MEASURE COMPANY, OF ROCHESTER, PENNSYLVANIA, A CORPORATION OF
DELAWARE.

DESIGN FOR CASING FOR A GASOLINE-DISPENSING PUMP.

Application filed June 20, 1924. Serial No. 9,926. Term of patent 14 years.

To all whom it may concern:

Be it known that I, WILLIAM S. TOWNSEND, a citizen of the United States, residing at Rochester, in the county of Beaver and State of Pennsylvania, have invented a new, original, and ornamental Design for Casing for a Gasoline-Dispensing Pump, of which the following is a specification, reference

being had to the accompanying drawing, forming a part thereof.

The figure is a perspective view of the casing for a gasoline dispensing pump.

I claim:

The ornamental design for casing for a gasoline dispensing pump, as shown.

WILLIAM S. TOWNSEND
